PACKAGE COMPRESSOR FOR TYING MACHINES

Alfred G. Suelflow, Milwaukee, Wis.; G. I. Hansen, executor of said Alfred G. Suelflow, deceased, assignor to Felins Tying Machine Company, Milwaukee, Wis., a corporation of Wisconsin

Application November 26, 1943, Serial No. 511,777

6 Claims. (Cl. 100—31)

1

This invention appertains to tying machines and more particularly to a novel attachment for such machines for holding and compressing packages and bundles during the tying operation.

In tying packages or bundles of goods, such as post office mail, gloves, stockings, etc., it is highly desirable that the bundles or packages be compressed and held just prior to and during the tying operation, so that not only will a tight tie be formed, but whereby the package or bundle will be compressed into a desired compact size.

It is therefore, one of the primary objects of my invention to provide means associated with the tying machine embodying a stationary jaw on the table on one side of the tying mechanism and a movable compressing jaw on the other side of the tying mechanism adapted to swing over the table toward the stationary jaw, whereby to effectively compress and hold a package or bundle between the same on the table to permit the effective tying of a tight, compact bundle.

Another salient object of my invention is to provide novel means for operating the swinging jaw over the table, whereby the desired pressure will be obtained with a minimum amount of exertion on the part of the operator.

A further object of my invention is to provide automatic means for setting the tying mechanism into operation for tying the bundle or package from the compressor after the actuation of the compressor by the operator for compressing the bundle or package.

A further important object of my invention is to provide novel means for mounting the stationary jaw on the table of the tying machine, whereby the same can be initially adjusted toward and away from the tying mechanism, so that different sizes of packages and bundles can be effectively handled.

A still further important object of my invention is to provide a novel compressor attachment for tying machine which will be durable and efficient in use, one that will be simple and easy to manufacture and one which can be incorporated with the tying machine at a small cost and with a minimum amount of change in the tying machine.

With these and other objects in view, the invention consists in the novel construction, arrangement and formation of parts, as will be hereinafter more specifically described, claimed and illustrated in the accompanying drawings, in which drawings:

Figure 1 is a side, elevational view of the tying

2

machine showing my novel compressor incorporated therewith, the movable jaw being shown in full lines in its inoperative position, and in dotted lines in its operative position, parts of the view being shown broken away and in section.

Figure 2 is a front, elevational view of the tying machine with my novel compressor incorporated therewith, the operating foot treadle being shown in full lines in its inoperative position and in dotted lines in its operative compressing position.

Figure 3 is a fragmentary, top, plan view of the table of the tying machine showing the compressor applied thereto, parts of the table being broken away to illustrate structural detail.

Figure 4 is a horizontal, sectional view taken substantially on the line 4—4 of Figure 2, looking in the direction of the arrows, illustrating the foot treadle mechanism.

Figure 5 is an enlarged, fragmentary, detail, vertical, sectional view taken substantially on the line 5—5 of Figure 3, looking in the direction of the arrows, illustrating the novel means employed for operating the clutch for setting the tying machine into operation.

Figure 6 is an enlarged, detail, vertical, sectional view through the table of the tying machine taken on the line 6—6 of Figure 1, looking in the direction of the arrows, illustrating the stationary jaw of the compressor.

Figure 7 is a detail, sectional view through the stationary jaw and table taken on the line 7—7 of Figure 6, looking in the direction of the arrows.

Referring to the drawings in detail, the letter A generally indicates my novel compressing attachment for the tying machine M.

The tying machine M is of the type shown and described in the pending application of Frank Radeck, Serial No. 409,676, filed September 5, 1941, which has issued as Patent No. 2,346,786, dated April 18, 1944. Hence, the tying machine will not be described in detail and only sufficient parts have been shown to enable the understanding of my compressor attachment A.

However, the tying machine M includes a supporting base frame 10 and this base frame can include corner uprights or standards 11 formed from angle iron or any other desired material. These legs or standards 11 can be connected together by longitudinal rails 12 and channel transverse rails 13. Mounted upon the upper ends of the legs or standards is a main base plate 14 on which various operating parts of the tying machine are mounted. Disposed above the base plate 14 is a table 15 on which the packages or bundles to be tied are placed. Brackets 16 can

be employed for connecting the table to the base plate.

Mounted upon the base plate 14 is the electric drive motor 17 and the armature shaft of this motor is connected through a worm 18 and pinion 19 to the rotatable clutch section 20 rotatably mounted on the main shaft 21 of the tying machine. Feathered upon the main drive shaft 21 is the clutch section 22 and the clutch section is normally urged into operative engagement with the clutch section 20 by a spring 23. When the clutch section 22 is in operative driving connection with the clutch section 20, the shaft 21 is driven for operating the various parts of the machine.

Normally holding the clutch section 22 out of operative engagement with the clutch section 20 is a pivoted trip lever 24. The outer end of the trip lever has formed thereon an inclined cam track 25 and a pin 26 extending radially from the clutch section 22 is adapted to engage said cam track at certain times. The trip lever 24 is rockably mounted intermediate its ends upon a stub shaft 27 and the trip lever is normally held in a lowered position with the cam track 25 in the path of the pin 26 by a leaf spring 28.

When the trip lever 24 is normally raised above the pin 26, the spring 23 moves the clutch section 22 into engagement with the clutch section 20 on the operating shaft 21. Upon the lowering of the trip lever 24 by its spring 28, the cam track end 25 thereof will rest upon the hub of the clutch section 22 and the pin 26 will ride into engagement with said cam track as the shaft 21 completes one revolution and as the shaft reaches the end of one complete revolution, the pin 26 riding on the cam track 25 will move the clutch section 22 out of engagement with the clutch section 20 and the shaft 21 will be brought to a standstill. The trip lever 24 is operated in a novel manner from my compressor attachment A and this will be later described.

The shaft 21 operates a needle mechanism 29, the knotter mechanism 30, the string holding mechanism 31, the cord tucker mechanism 32 and the string severing and bundle kicking mechanism 33.

My attachment A operates in conjunction with the main drive shaft 21 and the other parts of the tying machine function identically in the same manner as in the Radeck patent referred to above and hence said tying machine will not be described in further detail.

The attachment A comprises a rigid jaw or compressor plate 35 which is mounted transversely of the table 15 on one side of the knotting mechanism 30. This rigid jaw 35 is firmly secured to a strip 36 which extends entirely across the table and the ends of the strip hook over the edges of the table so that the strip can be moved toward and away from the knotting mechanism. This permits initial adjustment of the rigid jaw relative to said knotting mechanism and a set screw 37 can be employed for holding this rigid jaw in its preferred adjusted position.

Cooperating with the rigid jaw 35 is a swinging compressor jaw member 38. The jaw member 38 may include a pair of companion swinging arms 39 and these arms have rigidly attached thereto the compressor jaw faces 40 and the jaw faces and the upper ends of the arms are adapted to swing through slots 41 formed in the table 15 for that purpose. Hence the swinging jaw is movable toward and away from the rigid jaw 35 and swings toward and away from the knotting mech-

anism. The swinging arms 39 are mounted intermediate their ends upon a pivot pin 42 and this pivot pin is carried by a bracket 43 mounted upon the base frame 10 of the tying machine.

Also mounted for swinging movement upon the base frame of the tying machine is an operating lever 44 and the lever is mounted upon a pivot pin 45 carried by a bracket suspended from said base frame. The lower inner ends of the swinging arms 39 are operatively connected to the lever 44 by means of a link 46. Hence, upon movement of the lever 44, the swinging arms 39 will be actuated.

A treadle mechanism 47 is provided for actuating the lever and this treadle mechanism can include a pair of spaced parallel treadle arms 48, the outer ends of which are connected together by a treadle bar 49. The inner ends of the treadle arms 48 are pivotally connected, as at 50, to the base frame 10. The treadle member is normally held in an elevated position by contractile coil springs 51, the opposite ends of which are connected respectively to the treadle arms 48 and the base frame. By referring to Figures 1 and 2, it will be noted that the compressor arms 39 are normally held in their lowered inoperative position by a contractile coil spring 52, the opposite ends of which are connected respectively to one compressor arm 39 and to the base frame of the tying machine. A stop 53 is arranged in the path of the treadle mechanism to limit the upward swinging movement thereof under the influence of the springs 51. The operating lever 44 is operatively connected to the treadle 47 in any preferred manner, such as through the medium of a relatively stiff sprocket chain 54.

From the description so far, it can be seen that when an operator places his foot on the treadle bar 49 and pushes down on said treadle bar, the jaws 40 will be forcibly swung toward the rigid jaw 35 and that a bundle or package placed upon the tying machine table 15 will be compressed between the jaws 40 and the rigid jaw 35.

It is one of the important features of my invention to compress the bundle or package just prior to the operating of the tying machine and to hold the bundle or package in place during the tying operation and I have provided means for automatically setting the tying machine into operation when the treadle 47 reaches approximately the end of its lowered position.

The means for automatically setting the tying machine into operation includes a vertically sliding rod 55 and this rod can be mounted in suitable bearings carried by the base plate 14 of the base frame of the tying machine. The lower end of the rod 55 is operatively connected to the inner end of a foot pedal 56 and this foot pedal is rockably mounted intermediate its ends on a cross shaft 57 carried by the base frame. The forward end of the foot pedal can have formed thereon or secured thereto a foot plate 58. Hence it can be seen that when the foot plate 58 is depressed, the rod 55 will be forced upwardly. This rod extends up through the base plate 14 in front of the drive shaft 21 and the trip arm 24. Depending from the upper end of the rod 55 is a pivoted dog 59 and the lower end of the dog is provided with a tooth 60 which is adapted to catch and raise the outer end of the trip arm 24. The upper end of the pivoted dog is connected to the upper end of the rod 55 and it is to be noted that the tooth 60 projects laterally beyond the pivot point of said dog. Consequently, upon upward movement of the rod 55, the dog 59 will raise the

trip arm 24 above the pin 26 on the movable clutch section 22 and the clutch section will move inwardly into engagement with the driven clutch section 20 and the drive shaft 21 will be operated from the motor. When the dog 59 has been raised to a certain point, the outer end of the trip arm 24 will ride toward the free end of the tooth 60 which will swing the tooth and the dog on the pivot pin 61 out of the path of the trip arm allowing the trip arm to move back against the hub of the movable clutch section 22 under influence of the spring 28. This will again place the cam end of the trip arm 24 in the path of the pin 26 so that as the shaft completes one revolution, the pin will ride against said cam end and move the clutch section 22 from out of driving engagement with the drive clutch section 20, which will stop the operation of the machine. Upon the return of the rod 55 to its normal position, the tapered lower end of the dog will engage the cam arm 24 and the dog will be momentarily swung back so that the dog can again ride under the outer end of the cam arm 24. The rod 55 tends to return to its normal lowered position by its own weight, but obviously, a spring can be utilized to aid in this return, if such should be desired.

When the treadle 47 reaches approximately the end of its lowered position, a cross bar 62 carried by the treadle will strike the foot plate 58 and depress the same to elevate the rod 55 and start the tying machine into operation. A set screw 63 is preferably carried by the cross bar for engaging the treadle plate so that desired adjustments as to stroke of the treadle 47 and the pedal 56 can be made.

From the foregoing description, it can be seen that I have provided an exceptionally simple and durable compressor attachment for bundle tying machines which can be added to such machines at a small cost and which will automatically start the machine in operation.

Changes in details may be made without departing from the spirit or the scope of my invention, but what I claim as new is:

1. In a package and bundle tying machine, a table for receiving packages and bundles to be tied, a tying mechanism, means for compressing packages and bundles on said table prior to the tying operating including a stationary jaw on the table and a movable jaw mounted for swinging movement toward and away from the stationary jaw over said table, means for operating the movable jaw, and automatic means for setting the tying mechanism into operation from the operating mechanism for the movable jaw when said operating mechanism reaches approximately the end of its compressing stroke.

2. In a package and bundle tying machine, a supporting table for packages and bundles to be tied, a tying mechanism, a main drive shaft, means for operating the tying mechanism from the drive shaft, a motor for operating said shaft for throwing the tying mechanism into and out of operation, a clutch between said motor and shaft including a constantly driven clutch section rotatably mounted on the shaft and a movable clutch section feathered on said shaft, a device for compressing packages and bundles on the table including a stationary and a movable jaw, means for operating the movable jaw, and means for actuating the movable clutch section from said movable jaw operating means.

3. In a package and bundle tying machine, a

supporting table for packages and bundles to be tied, a tying mechanism, a main operating shaft, means for operating the tying mechanism from the shaft, a constantly operating motor, a clutch for operatively connecting the shaft with the motor including a movable clutch section, spring means normally urging the movable clutch section into driving position, a radially extending pin carried by the movable clutch section, a cam normally disposed in the path of the pin causing the pin to draw the movable clutch section out of driving position, a device for compressing packages and bundles on the table including a stationary jaw and a movable jaw, means for operating the movable jaw including a foot treadle, a slide rod, means for actuating the slide rod from the foot treadle as the foot treadle reaches the end of its stroke, and means for momentarily moving the cam out of the path of said pin upon upward sliding movement of said rod.

4. In a package and bundle tying machine, a supporting table for packages and bundles to be tied, a tying mechanism, a main operating shaft, means for operating the tying mechanism from said shaft, a constantly operating motor, a clutch for operatively connecting the shaft with the motor including a movable clutch section, spring means normally urging the movable clutch section into driving position, a radially extending pin carried by the movable clutch section, a cam normally disposed in the path of the pin causing the pin to draw the movable clutch section out of driving position, a device for compressing packages and bundles on the table including a stationary jaw and a movable jaw, means for operating the movable jaw including a foot treadle, a slide rod, means for actuating the slide rod from the foot treadle as the foot treadle reaches the end of its stroke, and means for momentarily moving the cam out of the path of said pin upon upward sliding movement of said rod including a pivoted dog carried by the upper end of said rod having a tooth for engaging said cam projecting laterally beyond the pivot point of said dog.

5. In a machine for tying packages and bundles, a table for receiving packages and bundles to be tied, means for compressing and holding packages and bundles on the table including a stationary jaw and a swinging jaw movable toward and away from the stationary jaw, a pivoted foot treadle, a swinging operating lever, means operatively connecting the swinging jaw to the lever and means operatively connecting the foot treadle to the operating lever, a driving mechanism for the tying machine including a clutch and means disposed in the path of the treadle for operating the clutch.

6. In a machine for tying packages and bundles, a table for receiving packages and bundles to be tied, means for compressing and holding the packages and bundles on the table including a stationary jaw and a swinging jaw movable toward and away from the stationary jaw, a pivoted foot treadle, a swinging operating lever, means operatively connecting the swinging jaw to the lever and means operatively connecting the foot treadle to the operating lever, a driving mechanism for the tying machine including a clutch and means disposed in the path of the treadle for operating the clutch, said means including a foot pedal and an adjustable member on the foot treadle for engaging the foot pedal.
